CLAIM

The ornamental design for a solar activated opening and closing device for use with vertical blinds, as shown and described.

DESCRIPTION

FIG. 1 is a front, top and side perspective view of the solar activated opening and closing device for use with vertical blinds showing my new design;

FIG. 2 is a front elevational view thereto, the rear being a mirror image of the front shown in FIG. 2;

FIG. 3 is a side elevational view thereof;

FIG. 4 is a side elevational view thereof;

FIG. 5 is a top plan view thereof; and,

FIG. 6 is a bottom plan view thereof.

The chain is partially shown for the sake of convenience. The chain and conduit are shown broken away to indicate indeterminate length.
